6 Claims. (Cl. 260—470)

1

The present invention relates to urethanes of aryl J acids, to a method of producing the same, and more particularly to such compounds in which the esterifying group of the urethane radical is aliphatic.

J acid or 6-amino-1-hydroxynaphthalene-3-sulfonic acid is a well known dyestuff intermediate finding extensive use as a coupling component in the preparation of azo dyes. The same is true of the aromatic J acids, i. e., compounds in which the amino group of the J acid is mono-substituted by an aromatic radical. The aromatic J acids, however, suffer from the disadvantage that they are highly unstable and are therefore difficult to prepare and store in a chemically pure state. Furthermore, they are insoluble in acids and hence cannot be employed in reactions in an acid medium. These objections to the aromatic J acids have prevented the extensive use of these highly desirable compounds in the preparation of dyestuffs.

J acid itself may be readily acylated to yield acyl derivatives thereof. The same is not true, however, of the aromatic J acids, these being very difficult to acylate. In fact, only one such derivative has been reported, namely, the formyl derivative characterized by Beilstein, volume 14, First Supplement, as 6-formyl-anilino-1-naphthol-3-sulfonic acid. According to Beilstein, this product is prepared by heating the parent phenyl J acid with 85% formic acid in the presence of sodium formate. The aforesaid compound has the following constitution:

The formyl derivative, however, is not readily prepared and moreover like the aryl J acids themselves, is highly unstable. As a matter of fact, the formyl derivative is almost immediately split by dilute mineral acids to regenerate the insoluble aryl J acid and formic acid. In addition, the formyl derivative when used as a "coupler" in the preparation of dyes produce products which yield dyeings of an entirely different shade from the parent aryl J acid.

We have now discovered a class of aromatic acid derivatives, to wit, the urethanes, which have properties far superior to the aryl J acids per se

or their formyl derivatives. Thus, the urethanes are easily prepared in a state of high chemical purity. They are stable, particularly to acids and alkalies, and may be kept for a long period of time without undergoing chemical decomposition. They are soluble in acids and accordingly may be employed in reactions involving an acid medium. Furthermore, when they are used as couplers in dye preparations, they yield dyes of the same general spectral character as those derived from the aryl J acids with the important exception that the dyeings obtained with the dyes prepared from the urethanes are superior in brightness to the dyeings obtained from the dyes prepared from the aryl J acids.

Accordingly, an object of the present invention is urethanes of aromatic J acids.

A further object of the present invention is urethanes of aromatic J acids in which the esterifying group of the urethane radical is aliphatic.

A further object of the present invention is to provide derivatives of aryl J acids which are superior to the aryl J acids and their formyl derivatives from the standpoint of stability, solubility and ease of preparation.

A further object of the present invention is to provide a new class of couplers which yield dyes capable of producing dyeings of a superior brightness as compared with the dyeings obtained with dyes prepared from aryl J acids.

A further object of the present invention involves a method of preparing urethanes of aryl J acids.

Other and further important objects of the invention will be apparent as the description proceeds.

The urethanes of aromatic J acids contemplated herein have the following structural formula:

40

50 in which Ar is an aromatic radical, i. e., phenyl, naphthyl, alkylphenyl such as tolyl, alkoxyphenyl such as anisyl, halogen phenyl such as chlorophenyl, bromophenyl, iodophenyl, fluorophenyl and the like, and R is an alkyl group such as

methyl, ethyl, propyl, butyl, amyl, octyl, decyl, octadecyl and the like.

The urethanes are prepared by reacting an aromatic J acid with an alkyl chlorocarbonate in the presence of an acid binding agent at low temperatures while agitating the reaction mixture. As aromatic J acids there may be utilized phenyl J acid, β -naphthyl J acid, p-anisyl J acid, p-methylphenyl J acid, p-chlorophenyl J acid, p-bromophenyl J acid, and the like. Suitable chlorocarbonates are methyl chlorocarbonate, ethyl chlorocarbonate, propyl chlorocarbonate, amyl chlorocarbonate, octyl chlorocarbonate, decyl chlorocarbonate, octadecyl chlorocarbonate, and the like. Suitable acid binding agents are inorganic alkalies such as sodium hydroxide, potassium hydroxide, sodium alcoholate, sodium carbonate and the like; or organic bases such as pyridine, quinoline and the like. Where the acid binding agent is inorganic, the reaction is generally carried out in an aqueous medium. However, where an organic binding agent such as pyridine is employed, it is preferable to carry out the reaction in the presence of an organic solvent for the aromatic J acid such as dimethyl formamide, diethyl formamide, formamide and the like. The reaction is effected by agitation of the ingredients at relatively low temperatures such as temperatures ranging from about 5 to 15° C. The low temperatures are maintained during the reaction by externally cooling the reaction mixture.

The urethanes, particularly those in which character R is a lower molecular weight alkyl group, are readily soluble in hot water and are not precipitated from such solutions by the addition of acid. The aqueous solutions of the urethanes are suitable for further condensation such as coupling reactions to produce azo and other dyes.

The invention is further illustrated by the following examples, in which the parts are by weight. It is to be understood, however, that the invention is not limited to these examples, the examples being illustrative only.

Example I

Ethyl urethane of phenyl J acid of the formula:

To a suspension of 37 parts of phenyl J acid (commercial product of 81% purity) in 200 parts of water are added 36 parts of 6 N sodium hydroxide solution. The mixture is stirred for 15 minutes and then treated with 12 parts of ethyl chlorocarbonate. The mass is rapidly agitated and maintained at approximately 5° C. by external cooling. After about 15 minutes, 17 parts of 6 N sodium hydroxide and 12 parts of ethyl chlorocarbonate are added and the mixture is stirred for another 15 minutes. A third portion of sodium hydroxide and ethyl chlorocarbonate is then added as above.

An oil separates out which gradually becomes crystalline and is completely solid after an hour of stirring. This substance is removed by filtration, and dissolved in water. The solution is then

cooled to 30° C. and treated with salt solution to the point of incipient cloudiness. Upon cooling and seeding, the sodium salt of the ethyl urethane of phenyl J acid separates slowly as microscopic needles.

Example II

The procedure is the same as in Example I excepting that p-anisyl J acid is substituted for the phenyl J acid. The ethyl urethane of p-anisyl J acid is obtained as a highly insoluble sodium salt which separates from the reaction mixture as well-formed flat plates.

Example III

The procedure is the same as in Example I excepting that p-methyl phenyl J acid is used in place of the phenyl J acid in the above procedure. The ethyl urethane of p-methyl phenyl J acid is obtained as the sodium salt in the form of fine needles.

Example IV

The procedure is the same as in Example I excepting that p-chlorophenyl J acid is utilized in place of the phenyl J acid. The ethyl urethane of p-chlorophenyl J acid is obtained as the sodium salt in the form of microscopic crystals.

Example V

The procedure is the same as in Example I excepting that butyl chlorocarbonate is employed in lieu of the ethyl chlorocarbonate. The product, obtained in the form of the sodium salt, is butyl urethane of phenyl J acid of the following formula:

Example VI

To a solution of 20 parts of highly purified anhydrous pyridine salts of phenyl J acid in 100 volumes of dimethyl formamide containing 8 parts of pyridine are added 17.5 parts of octadecyl chloroformate at 10° C. The mixture is agitated during the addition and maintained at 10° C. by external cooling. After 4 hours at 10° C., an additional 20 parts of pyridine and 17.5 parts of octadecyl chloroformate are added and the mixture stirred at 10° C. for another 4 hours. Finally, the mass is stirred at room temperature for 16 to 20 hours. The resulting suspension is then treated with 250 volumes of benzene and stirred for 1/2 hour. Two phases separate and the lighter, larger layer is freed from suspended material by filtration through a layer of diatomaceous earth. The filtrate is evaporated to dryness and the residue is extracted with two 300-volume portions of low boiling petroleum ether. The resulting yellow solid is dried and dissolved in a minimum quantity of hot benzene. A small amount of insoluble material is removed by filtration and the filtrate is maintained for one hour at 5 to 6° C., whereupon the octadecyl urethane of phenyl J acid crystallizes out as the pyridine salt in the form of plate-like crystals. The product is cooled and dried. It may be further purified by recrystallization from alcohol and water.

The product has the following formula:

Various modifications of the invention will be apparent to those skilled in the art and therefore I do not intend to be limited in the patent granted except as required by the prior art and the appended claims.

I claim:

1. Compounds of the following structural formula:

wherein Ar is selected from the group consisting of phenyl, lower alkylphenyl, lower alkoxyphenyl and halogenphenyl and R is an alkyl radical, and the salts thereof.

- 5   2. The ethyl urethane of phenyl J acid.
- 3. The ethyl urethane of p-anisyl J acid.
- 4. Octadecyl urethane of phenyl J acid.
- 5. The ethyl urethane of p-chlorophenyl J acid.
- 6. The butyl urethane of phenyl J-acid.

VSEVOLOD TULAGIN.
